LUDWIG SPACHTHOLZ AND JOSEPH WINGERSON, OF KITTANNING, PENNSYLVANIA.

GRINDING PLATE-GLASS.

No. 921,477.

Specification of Letters Patent.

Patented May 11, 1909.

Application filed December 14, 1907. Serial No. 406,459.

To all whom it may concern:

Be it known that we, LUDWIG SPACHTHOLZ and JOSEPH WINGERSON, residents of Kittanning, in the county of Armstrong and State of Pennsylvania, have invented certain new and useful Improvements in Grinding Plate-Glass, of which the following is a specification.

This invention provides for grinding plate glass by causing plates of glass to bear face-wise and move one upon the other in such manner that both faces are ground simultaneously.

One feature of the invention is the grinding of several relatively small "runner" plates while grinding a large plate or field. By preference, the area of each of the runners is a fraction of the area of the large plate—say approximately one-fourth, so that by applying two of the runner plates at one time to the surface of the large plate, those two runner plates may be ground while grinding the face of the large plate.

As further characteristic of the improved practice, a certain number of runner plates are rough-ground while rough-grinding the large plate, and then the same runner plates are smooth-ground while similarly grinding the large plate. Thus, if the area ratio is 4 to 1, two of the runner plates are applied to the large plate and by the time they are completely rough-ground about one-half of the process of rough-grinding the large plate has been accomplished. The two runner plates

are then removed and two other unground plates substituted, and by the time the substituted plates have been fully rough-ground, the rough-grinding of the large plate has been completed. The smooth-grinding of the plates may then proceed without removing the last applied runner plates until they have been smooth-ground and are ready for the final polishing. When this has been accomplished, the process of smooth-grinding the large plates has proceeded about one-half toward completion. The runner plates that were first rough-ground are then substituted for the smooth-ground runners, and by the time the smooth-grinding of these substituted plates has been accomplished the smooth-grinding of the large plate has been completed. By thus grinding one plate upon another, practically double the area is ground as compared with the old practice of grinding a single surface by means of iron or other runner or grinding devices. In addi-

tion to increasing the output, the expense of maintaining the runner faces is wholly eliminated, and as such runners wear quite rapidly the cost of keeping them in working condition is considerable.

In practicing the invention, it is immaterial whether the runners are positively driven, or propelled solely by their engagement with the large plate ordinarily carried by a rotating table.

Apparatus for practicing the method and also embodying the improved devices is illustrated in the accompanying drawings, Figure 1 being a side elevation thereof, partly in section, one of the runners being shown raised. Fig. 2 is a top plan view of the table and runners, one of the latter showing a clamping mechanism while only the top surface of the other detachable runner head is shown. Fig. 3 is a vertical sectional view on a larger scale of one of the runners. Figs. 4 and 5 are detail views of the clamping device. Fig. 6 illustrates a modification of the runner-connecting gearing.

Referring to the drawings, 2 designates the large rotating table supported on the central shaft or axle 3, the table and its rotating means being of the usual well known construction.

4 designates a frame above the table, and in the embodiment here illustrated two vertical runner shafts 5 are journaled therein, each carrying at its lower end the four horizontally radiating arms 6.

7 designates the runner heads. By preference each head is formed of cast iron, with its upper surface reinforced by circular flange 8 and the four ribs 9 radiating from the center to the flange. The top faces of these ribs are flat like the under surfaces of arms 6 which register therewith and bear thereon when the head is in position.

For securing the head, two clamping devices are preferably employed at opposite sides of the center, the same being carried by two of the arms 6. Each device consists of an inverted U-shaped yoke member 10 having its opposite arms slotted vertically at 11 to move on the transverse pin 12 in arm 6. The lower extremities of the yoke-arms are formed with hooks 13 to engage pins or lugs 14 projecting from opposite sides of rib 9. The threaded stem 15, operating through the upper end of the yoke by means of hand wheel 15', raises and tightens the clamp with the hooks engaging lugs 14. Two of these

clamping devices operate to securely hold the runner head, and they are of such construction and may be so manipulated that the runners may be quickly and conveniently released. To accurately center the runners and hold them centered, each shaft 5 may be projected at 16 to enter a corresponding central depression 16' in the runner, and a pin or lug 17 may be similarly projected from each of arms 6 to enter a depression 17' in each of ribs 9. The runner heads are preferably square. For a table thirty feet in diameter each of the two heads may be 12 feet square. By so operating the runners that the corners of one runner approach the edges of the other runner between its corners, there is no danger of collision, while at the same time their paths of movement so overlap as to effectually operate on the whole area of the table. For thus maintaining the runners they may be geared together directly by wheels 18, as in Fig. 2, and thus rotate in the same direction, or by interposing a pinion 19 between gears 18, as in Fig. 6, they may be driven in reverse directions.

In operation, a plate or field of glass 20 is cemented on table 6 in the usual manner, while a plate 21 is similarly centered to the under face of each of the runners. With two of the runners in position, the rough-grinding proceeds, sand and water being applied as in the present practice. As here shown the runners are propelled by their contact with the table, but they may be positively driven. No novelty is claimed in this connection, as in the present practice the runners are in some instances driven only by the table and in others are positively driven. As the area of glass on the table is much larger than the combined areas of the two runners, being double in the example here given, the rough-grinding of the runner plates 21 is completed by the time the rough-grinding of the large plate 20 is approximately one-half finished. At this stage the machine is stopped, and the two runner heads 7 carrying the fully rough-ground plates are removed and similar heads with fresh plates are substituted for them. The operation then proceeds, and by the time the substituted plates have been rough-ground, the rough-grinding of large plate 21 has been completed. The plates are then ready for the smooth-grinding process in which a finer abrasive, such as emery, is used. This may proceed at once, the runner plates last rough-ground being the first to be smooth-ground, hence those plates are not removed from the machine from the time they are first applied until after the whole grinding operation has been completed and they are ready for polishing. By the time these runner plates are fully smooth-ground the same process has been approximately one-half completed as to the large plate 21, and is fully completed

along with the smooth-grinding of the set of runner plates which were first rough-ground.

For connecting and disconnecting the runners, each of shaft 5 may be raised and lowered in frame 4 by a lever 22. It will be noticed in this connection that the runner-connecting gears are of such width that this vertical movement of the shaft does not disengage them, and hence the positioning of the runners with relation to each other is always maintained.

It will be understood that what we term the glass plate or field 21 on table 2 is in practice usually made up of a number of plates of various shapes and areas, the purpose being to cover the table as fully as possible. The same is true of the smaller or runner plates. While some plates may be the exact size of the runners, it more often happens that their surfaces are covered with several plates. Hence, in referring to the runner plates and to the large or table plate, we do not necessarily mean a single plate but rather a glass covered surface or field which may be made up of one plate or several, according to circumstances.

The apparatus herein shown and described forms the subject matter of our application Serial No. 417,766, filed February 25, 1908.

We claim:—

1. That improvement in the art of grinding plate glass by facewise contact of several small plates with a large plate, consisting in supporting some of the small plates in facewise engagement with the large plate, moving the engaging plates relatively to each other for fully grinding the smaller plates while partially grinding the large plate, substituting other smaller plates for those fully ground, and again moving the engaging plates relatively to each other for fully grinding the substituted smaller plates and completing the grinding of the large plate.

2. That improvement in the art of grinding plate glass consisting in rotating smaller plates of glass in facewise engagement with a larger plate, such smaller plates having a combined area less than the large plate, causing the plates to move with relation to each other so as to complete the rough-grinding of the smaller plates while partially grinding the large plate, substituting other small plates for those completely rough-ground, and simultaneously completing the rough-grinding of the substituted smaller plates and the larger plate.

3. That improvement in the art of grinding plate glass consisting in causing small plates of glass to movably bear facewise and successively on the face of a large plate of glass for completely rough-grinding a plurality of small plates while similarly grinding the large plate, and then causing the small rough-ground plates to bear face-wise and successively on the rough-ground large plate,

whereby the several smaller plates are smooth-ground while smooth-grinding the large plate.

4. That improvement in the art of grinding plate glass consisting in rotating a large plate of glass, rotatably supporting smaller plates of glass in facewise engagement with the large plate, completing the rough-grinding of a plurality of small plates by substituting one small plate for another while rough-grinding the large plate, and smooth-grinding the large plate and all of the smaller plates by causing the several rough-ground small plates to successively facewise engage the rough-ground large plate, whereby all of the small plates are smooth-ground upon completing the smooth-grinding of the large plate.

5. That improvement in the art of grinding plate glass consisting in rotating a large plate, rotatably supporting smaller plates in facewise engagement with the large plate,

completely rough-grinding the small plates when partially rough-grinding the large plate, removing the rough-ground small plates and substituting other small plates, simultaneously completing the rough-grinding of the substituted plates and the large plate, then completely smooth-grinding such substituted plates while partially smooth-grinding the large plate, replacing the completely smooth-ground small plates by the previously removed rough-ground small plates, and then simultaneously completing the rough-grinding of the last named small plates and the large plate.

In testimony whereof we affix our signatures in presence of two witnesses.
